Joseph A. Rayder
INVENTOR

BY Alfred T. Brattore

ATTORNEY.

UNITED STATES PATENT OFFICE.

JOSEPH A. RAYDER, OF PHILADELPHIA, PENNSYLVANIA.

APPLICATOR BRUSH.

Application filed August 31, 1922. Serial No. 585,408.

To all whom it may concern:

Be it known that I, JOSEPH A. RAYDER, a citizen of the United States, residing at Philadelphia, in the county of Philadelphia and State of Pennsylvania, have invented a new and useful Applicator Brush, of which the following is a specification.

This invention relates generally to applicator brushes having a controllable feed 10 to the brush proper consisting of a collapsible tube, such as are used for shaving, painting, varnishing and analogous purposes.

More specifically this invention has reference to certain improvements in applicator 15 brushes of the character described in my prior Patent Number 1,426,909, dated August 22nd, 1922, and it has for its primary object to provide an applicator brush which is sanitary in every respect, that is to say, 20 corrosion or fouling of the soap ejector portion of said brush when used under ordinary conditions cannot take place.

Another object of my present invention is to provide an applicator brush having a 25 more or less collapsible container provided with an ejector nozzle adapted to effectively project all the required amount of soap or other substance desired for a particular application clear of the discharge outlet into 30 the bristles of the brush.

A further object of this invention is the provision of an applicator brush of the character referred to, the container portion whereof serves when collapsed or compressed 35 to eject the requisite amount of substance to be applied at any one time, means being provided in connection therewith for cutting off the feed therefrom to the brush during the process of application.

A still further object of my invention is to provide an applicator brush of the type referred to which comprises a minimum number of parts, the same being simple in character, easy to manufacture and assemble, 45 while of a serviceable and reliable character for the purposes had in view.

With the foregoing and other objects in view, as will be more clearly apparent from the following description, my invention consists essentially in the novel features of construction, combinations and arrangements of parts hereinafter fully described, illustrated by the accompanying sheet of explanatory drawings, and more specifically defined by 55 the subjoined claims.

In the drawings:—

Figure 1 is a partly sectional longitudinal view of an applicator brush embodying one form of my present invention.

Figure 2 is a fragmentary central section 60 through the brush head and connected container, the same being drawn to an enlarged scale for a clearer illustration of the functioning of my novel applicator brush; and

Figure 3 is a similar enlarged fragmentary sectional view of a slightly modified form of the invention.

Referring more particularly to Figures 1 and 2 of the drawings and in accordance with the embodiment of my invention illustrated thereby a collapsible foil container of appropriate material is designated by the numeral 4, the same being closed at one end 5, and adapted for rolling up by means of a slotted key 6 in the well known way. This 75 container or cylinder 4 is formed with an integral screw threaded neck portion 7 and it is shouldered at 8 for a purpose later on explained. It is also to be particularly noted that the container or cylinder screw threaded neck portion 7 is formed with an axial 80 and conical extension 9 projecting from the convex end part 10 thereof, and said conical extension 9 and neck portion 7 are provided with a longitudinal tapered passage 11 therein, said tapered passage 11 terminating at its outer end in communication with outwardly inclined radial ducts 12 for a purpose later on explained.

Removably fitting the aforesaid screw 90 threaded neck portion 7 is the brush head 13 which is concaved at 14 and of appropriate dimensions to snugly seat upon the aforesaid convex end part 10 and shoulder 8 when screwed thereon, as will be clearly understood on an examination of Figure 1 more particularly. This brush head 13 is cupped or dished out at 15 to receive the bristles or brush proper 16, and it is centrally formed with an integral inverted funnel shaped portion 17 of an internal taper or bore 18 corresponding with the exterior taper of the above described axial and conical extension 9 on the neck portion 7.

In some instances or cases where the 105 user of my novel applicator brush prefers to use a tube of substance other than that supplied in the containers supplied by me and where such a container 4' is of the ordinary or standard type provided with a screw 110

threaded neck 19—Figure 3—from which has been removed the ordinary cap—not shown,—I provide the attachment 20 shown in said figure. This attachment 20, as will 5 be readily understood serves the purpose of the above described integral head or neck portion 7 and it is of identical shape and dimensions, that is to say it comprises an extension 9', longitudinal tapered passage 10 11', radial ducts 12' and convexed end part 10'.

From the foregoing description it will be readily seen that by slightly unscrewing the brush head 13 a desired quantity of 15 soap or other substance contained in the foil container 4 or 4' can be readily ejected through the tapered passage 11 and radial ducts 12 into the bore 18 of the funnel shaped part 17 whence it will exude through 20 the open or outer end thereof centrally into the bristles of the brush 16, whereupon it can be applied to the part or parts desired in the well known manner. It is to be particularly observed that before the application of the soap or other substance is 25 made to the part or parts under treatment the user will re-screw the brush head 13 tight upon its seats 8 and 10 which will insure a clean ejection of said soap or other 30 substance out of the inverted funnel shaped portion 17, and in order to further insure effective operation of the device in this connection I make the point or apex 21 of the axial and conical extension 9 of a dimension 35 to be projected slightly beyond the open end of the inverted funnel shaped portion 17, when the parts 13 and 4 or 13 and 20 are screwed together out of use. It will, of course, be readily understood that where 40 the attachment 20 is used it will firstly be screwed tight upon the neck 19 of the tube 4' so that the manipulation of the brush head 13 will not effect its displacement under ordinary conditions. Still further it will be 45 readily seen that by my invention I have made an important advance in the art whereby a perfectly sanitary applicator brush results, as a very slight turn of the brush head 13 will suffice for the ejection of what- 50 ever amount of the soap or substance from the container 4 or 4' is required, while the peculiar formation and co-related disposition of the parts 9 and 17 effectively prevents any of said soap or other substance

from collecting or lodging in the tapered bore 18, whereas the apex 21 always insures a clear outlet therefrom.

An examination of the drawings and foregoing description will fully clarify the advantages inhering to my novel structure 60 of applicator brush as well as its obvious uses other than the specific form set forth, and it will be further readily understood that while I have described practical embodiments of my present invention the same 65 is susceptible of modification, and the right is therefore hereby reserved to make such reasonable variations therein as fairly fall within the scope of the appended claims.

Having described my invention, what I 70 claim as new and desire to secure by Letters Patent is:—

1. In combination, an applicator brush having a base portion provided with a screw threaded recess and having a conical 75 passage in communication therewith, a resilient receptacle in threaded engagement with said base portion, a conical extension on said receptacle adapted to be disposed in close contact with the interior of the 80 aforesaid conical passage, the apex of said extension being substantially coextensive with the apex of the conical passage when these two elements are in contact whereby the aforesaid conical passage may be completely closed by the aforesaid extension, the said conical extension being provided with one or more passages for communication 85 between the interior of the receptacle and the aforesaid conical passage, and 90 means to compress said receptacle.

2. An article of manufacture consisting of a cylindrical portion in communication with a conical portion, said cylindrical portion being screw threaded interiorly and 95 adapted to engage the nipple of a resilient receptacle, said cylindrical portion being also screw threaded exteriorly thereof and adapted to engage a similar screw threaded portion of a brush, and the aforesaid conical portion having passages through the walls thereof, whereby a resilient receptacle may be detachably engaged by a brush and communication between the interior of the 100 resilient receptacle and the bristles of the 105 brush established.

JOSEPH A. RAYDER.
